UNITED STATES PATENT OFFICE.

JAMES BOYD, OF ST. PAUL, MINNESOTA.

HOISTING-MACHINE.

SPECIFICATION forming part of Letters Patent No. 443,719, dated December 30, 1890.

Application filed September 15, 1890. Serial No. 365,067. (No model.)

To all whom it may concern:

Be it known that I, JAMES BOYD, a citizen of the United States, residing at St. Paul, in the county of Ramsey and State of Minnesota, have invented certain new and useful Improvements in Hoisting-Machines, of which the following is a specification.

This invention relates to that class of hoisting-machines in which the drum for the hoisting-cable is capable of being revolved at different speeds; and it consists in the arrangement of the mechanism whereby the change of speed is accomplished or the motion stopped, as hereinafter shown and described, and specifically pointed out in the claims.

In the drawings, Figure 1 is a sectional side elevation. Fig. 2 is an end elevation, partially in section. Fig. 3 is a plan view, and Fig. 4 is a side view, of the cam-shifting mechanism detached to illustrate its construction and mode of operation more fully. Fig. 5 is a perspective view of one of the shifting-straps removed. Figs. 6 and 7 are enlarged perspective views of the cam-shifting collars detached. Fig. 8 is a perspective view of the pawl-actuating lever detached.

A is the base-frame, on which the cable-drum B is mounted by hanger or standard D D' and provided with the usual ratchet-teeth a' and brake-rim a².

E is an upright shaft journaled in the standard D', and to whose upper end the "sweep" F is attached.

Upon the drum B are two bevel-gears G' G² of different sizes, and upon the shaft E are two bevel-gears H' H². These gears H' H² are connected to the shaft E by a feather b, so that they may be moved upward and downward upon the shaft, but will at the same time revolve with the shaft. The gear H' when elevated engages with the small gear G², and the gear H² when elevated engages with the larger gear G'.

Beneath the gear H', fast upon the horizontal member D² of the frame D', is a cam-collar K', having two inclined cam-surfaces d' d², adapted to engage with similar cam-surfaces d³ d⁴ on another cam-collar K² beneath the gear H' and loose upon the shaft E, while a similar cam-collar K³ is secured upon the lower member D³ of the standard

D', and is provided with cam-surfaces d⁵ d⁶, adapted to engage with similar cam-surfaces d⁷ d⁸ on another cam-collar K⁴ beneath the gear H². The function of these cam-collars 55 is to elevate the gears H' H² when the loose collars are oscillated beneath the hubs of the gears, and thus throw them into and out of mesh with the gears G' and G².

The cams on the collars are of peculiar construction and are adapted to produce certain peculiar movements to the gears H' H², so as to elevate one while depressing the other, and also to hold both the gears H' H² out of mesh with the gears G' G². To accomplish this, 60 each cam-collar is formed with two projections with flat surfaces d⁹, occupying about one-eighth of the circumference, and straight on one side at d¹⁰ and inclined on the other at d' d² d³ d⁴, the inclined portions each occupying about one-eighth of the circumference. The remainder two surfaces d¹¹ d¹² each occupies 65 about one-fourth of the surface. It will be seen, then, that when the two collars are in position and the loose collar turned upon 70 the fixed collar a movement of one-eighth of a revolution may be obtained without raising the movable collar by the opposing inclines.

By arranging the inclines of the two sets of collars in reverse order the movable collars can be actuated by turning them back and forth in the same direction. Hence if levers be attached to the two movable collars and turned one-fourth of a revolution in one direction the collar K² will elevate the gear 85 H', while at the same time the collar K⁴ will depress the gear H², or vice versa, and by reason of the flat surfaces d¹¹ d¹² there is a point where both gears H' H² are held out of mesh with the gears G' G². This is a very important advantage, as I can thus accomplish 90 all the required movements with one lever, either to change the speed or stop the machine.

I have shown in Figs. 3, 4, and 5 an arrangement of levers operating the movable collars which has been found to work in a satisfactory manner. Each of the movable collars is surrounded by a strap M', having two oppositely-placed upright slots g' g², into which 95 pins g³ in the collars K² K⁴ rest. By revolving the straps the collars are turned and

moved upward or downward on the shaft, while at the same time, by the presence of the slots $g' g^2$, the straps remain in the same horizontal plane. The straps are provided 5 with arms M^2 , projecting outward between the gears and united to one common handle M^3 . The arms M^2 may be curved or bent and carried to any point of the machine for the convenience of the operator.

10 N' is a pawl, pivoted at m' to the frame A and adapted to engage with the ratchet-teeth a' on the drum B.

15 N² is a substantially horizontal lever, pivoted at m^2 to the frame A and with one end m^3 fitting through a hole in the pawl N', while the other end projects toward the gears H' H², and is provided with a raised portion m^4 , adapted to be acted upon by the arm M^2 or other form of lever which operates the cam- 20 collars, so that when the arm M^2 is oscillated it will force the end m^4 of the lever downward, and by correspondingly elevating the other end cause it to throw the pawl N' out of contact with the ratchet-teeth on the drum.

25 If it is desired to merely reverse the position of the cam-collars, the arm M^2 will merely actuate the lever N² and pass over it, allowing the pawl to immediately return to its contact with the ratchet-teeth; but if it is desired to disengage both the gears H' H² from the gears G' G², which is done by holding the arm M^2 in its central position, then the lower side of the arm M^2 will, by resting upon the raised portion m^4 of the lever N², hold the 35 pawl N' out of contact with ratchet-teeth on the drum B, which is the required position when the drum is disconnected from its driving-gearing.

Having thus described my invention, what 40 I claim as new is—

1. In a hoisting-machine, a drum B, having gears G' G² of different sizes connected thereto, an upright shaft E, carrying gears H' H², adjustable thereon but adapted to be 45 revolved therewith, stationary collars K' K³, having alternating cam-surfaces and flat surfaces, and movable collars K² K⁴, having corresponding opposing cam and flat surfaces,

and adapted to be alternately oscillated beneath said gears H' H² to alternately connect 50 them with said gears G' G² or to hold them disconnected thereon, substantially as and for the purpose set forth.

2. In a hoisting-machine, a drum B, having gears G' G² of different sizes connected thereto, 55 an upright shaft E, carrying gears H' H² slidable thereon, but adapted to be revolved therewith, stationary collars K' K³, having alternating cam-surfaces and flat surfaces, and movable collars K² K⁴, having corresponding 60 opposing cam and flat surfaces, and with pins g^3 in said movable collars, in combination with connected straps M', inclasping said movable collars and provided with slots $g' g^2$, fitting over said pins, whereby said collars 65 may be oscillated by the horizontal movement of said connected straps, substantially as and for the purpose set forth.

3. In a hoisting-machine, a drum B, having gears G' G² of different sizes connected thereto and with ratchet-teeth a' , an upright shaft E, carrying gears H' H², adjustable thereon but adapted to be revolved therewith, stationary collars K' K³, having alternating cam-surfaces and flat surfaces, and movable collars K² K⁴, having correspondingly-opposing 70 cam and flat surfaces, and with pins g^3 in said movable collars, straps M', inclasping said movable collars, and with slots $g' g^2$, fitting over said pins, and with arm M^2 , connecting 75 said straps, pawl N', adapted to engage with the ratchet-teeth on said drum, pivoted lever N², with one end in contact with said pawl and with the other end beneath said arm M^2 , whereby said pawl will be actuated by the 80 oscillation of said arm and be placed in co-action with said cam-collars and gears, substantially as and for the purpose set forth.

In testimony whereof I have hereunto set my hand in the presence of two subscribing 85 witnesses.

JAMES BOYD.
